UNITED STATES PATENT OFFICE.

ABRAM W. STEVENS AND LE ROY W. STEVENS, OF AUBURN, NEW YORK.

WAGON-AXLE.

SPECIFICATION forming part of Letters Patent No. 240,859, dated May 3, 1881.

Application filed February 28, 1881. (No model.)

To all whom it may concern:

Be it known that we, ABRAM W. STEVENS and LE ROY W. STEVENS, of Auburn, in the county of Cayuga and State of New York, have invented new and useful Improvements in Wagon-Axes, of which the following is a specification.

Our invention relates to improvements in axles for various kinds of wagons, particularly those used to carry thrashing-machines, requiring to be longer than for ordinary wagons, and at the same time light and strong; and the objects of our improvements are to provide a trussed axle having its skeins united by adjustable truss-bolts, in combination with a central support or connection, to which both bolts are secured, said connection being pendent from the bridge or bridges placed under the axle, and also to provide axle-skeins made with a tubular bolt-receiver and an open recess, to hold the body and the eccentrically-formed head of the truss-bolts.

To obtain the best results from truss-bolts it is desirable that they should be as much as possible diverging from a parallel line with the axle, and yet not to hang so low as to give to the axle an unsightly appearance.

Various kinds of truss-rods and devices have been used in connection with the body of axles to obtain the desired strength. The skeins have been provided with lugs, on the under side thereof, through which truss-rods pass to unite them. The truss-rods most generally pass through a portion of the axle and issue at the end of the skeins; but boring the axle for that purpose weakens it. Truss-rods have also been united under the center of the axle with a double screw-bolt having a nut in the center of its length.

Our invention will first be described in connection with the drawings, and then pointed out in the claims.

In the drawings, Figure 1 represents a rear view of an axle constructed according to our improvement, one end of the axle being shown in section. Fig. 2 represents a bottom view of the same. Fig. 3 represents a rear view of the axle provided with stays above the truss-rods and a turn-buckle with a central opening for the reception of the king-bolt. Fig. 4 represents, in perspective, the casting forming

the lower bridge and pendent post of the axle-truss. Fig. 5 is a view of the lower brace, usually projecting from the central reach or perch of wagons. Fig. 6 is a view of one of 55 the truss-bolts.

In said drawings, A represents the wood axle, and B the skeins thereof. Each skein is provided with a shoulder or collar, b, as inner support for a wheel, and a nut, b', to retain it 60 thereon, and also with a tubular receiver, B', on the under side thereof, to hold a truss-rod, C. The shoulder b is recessed at b² to receive the head of a truss-rod as near as possible to the body or skein of the wooden axle, and the 65 head c of each truss-rod is made eccentric, with the same object in view.

In the center of the axle, on the bottom thereof, is secured, with bolts or screws, a casting, D, in the form of an inverted bridge or support, provided with a pendent post, D', to receive and retain the inner ends of the truss-bolts by means of nuts c² bearing against opposite sides of said support. The bridge-plate D is recessed in the center for the reception 75 of the lower brace, E, of the central reach of wagons. Its recessed portion, extending forward of the axle, is provided with an opening, d, for the reception of the lower end of the king-bolt. By using this recessed bridge-plate 80 D the lower end of the brace E is constantly supported, and the use of a nut or a key on the lower end of the king-bolt can be dispensed with. The king-bolt F can also be made to pass through the center of the axle, as shown 85 in Fig. 3. In this case two stays or bridges, G, are secured to the under side of said axle, and a link turn-buckle, H, is used to connect the ends of the truss-rods C, one of which rods should have a right-hand thread and the other 90 a left-hand thread cut thereon. The link H being of such size as to receive the end of the king-bolt, it will be locked thereby, and at the same time give the desirable support to the brace E, the latter receiving the king-bolt between the bottom of the axle and the turn-buckle link H. 95

Having now fully described our invention, we claim—

1. The combination of an axle and axle-skeins, provided with tubular receivers B' and recesses b², with truss-rods having eccentric-

heads, and a central support to unite the ends of the rods and receive the lower brace and king-bolt of a wagon running-gear, substantially as and for the purpose described.

5 2. The combination of an axle and axle-skeins, having tubular receivers for truss-rods provided with eccentric heads, and a central support, D, for the perch-brace E and king-

bolt, with a pendent post, D', to receive the ends of truss-rods, substantially as and for the purpose described.

ABRAM W. STEVENS.
